TONGS

Lawrence F. Baash, Los Angeles, and William H. Maxwell, Beverly Hills, Calif.

Application March 18, 1930. Serial No. 436,695

1 Claim. (Cl. 81—128)

This invention relates to tools and relates more particularly to tongs for handling pipe, tubing, and like objects, and a general object of the invention is to provide a simple, effective and improved tool of this character.

Another object of the invention is to provide tongs that are particularly sturdy in construction and which embody but few simple parts.

10 Another object of the invention is to provide a tool of the character mentioned which embodies a gripping jaw and cam means for operating the jaw adapted to be directly operated by a line or the like employed to operate the tool.

It is another object of the invention to provide tongs which are well balanced and easy to operate and which may be constructed to withstand hard usage.

20 It is a further object of the invention to provide tongs of the character mentioned in which the means for operating the gripping jaw are housed and protected against injury and may be constructed sufficiently heavy to withstand hard usage, and excessive strains, without making the tool bulky or unbalanced.

Another object of the invention is to provide tongs of the character mentioned in which the line for operating or turning the tongs and for 30 operating the gripping jaw connects to the tool at a point a substantial distance from the pipe carrying part of the tool so that a great leverage is obtained for turning the tongs.

Other objects and features of our invention 35 will be best and more fully understood from the following detailed description of a typical form and application of the invention, throughout which description reference is had to the accompanying drawing, in which:

40 Fig. 1 is a side elevation of the tongs provided by our present invention illustrating the tool engaging a pipe. Fig. 2 is a top or plan view of the tongs. Fig. 3 is a longitudinal detailed sectional view of the device. Fig. 4 is an 45 enlarged detail sectional view of the head portion of the tool, and Fig. 5 is an enlarged transverse detail sectional view as indicated by line 5—5 on Fig. 3.

The tool provided by our present invention 50 is capable of embodiment in tongs, for handling various types of objects. Throughout the present disclosure of the invention we will describe it as embodied in tongs for handling pipe or casing. It is to be understood that the invention 55 is not to be construed as restricted to the

particular form or application of the invention about to be described, but is to be taken as including any features or modifications that may fall within the scope of the claim.

The tongs provided by this invention includes, 60 generally, pipe engaging means 10, a pipe gripping element or jaw 11 carried by the means 10, a handle 12 for the means 10, means 13 on the handle 12 for operating the jaw 11, and means 14 for returning the gripping jaw 11 65 to a retracted position after operation.

The pipe engaging means 10 is preferably such as to embrace or encircle a pipe P and carries the jaw 11 for gripping a pipe. The means 10 is in the nature of a head and may be designed in various manners for handling pipe or like objects of various different sizes and shapes. In the case illustrated the means 10 includes a main or body part 15 and an outer part or closure element 16. 70

The body part 15, in the preferred embodiment of the invention, carries the gripping jaw 11 and is formed or provided with the operating lever or handle 12. The body part 15 may be a single rigid part yoked or U-shaped in its general configuration so that it has two spaced side parts 17 and 18 and a central recess or opening 19 between the side parts. The opening 19 is provided to carry the gripping jaw 11 80 and is shaped to slidably receive or carry the jaw. The sides or side walls 21 of the opening 19 are preferably made parallel and flat to slidably receive the sides of the gripping jaw 11. The inner portion of the opening 19 may 85 be in the nature of a socket or recess, that is, the body part 15 may have what we will term its upper and lower portions extending over the inner portion of the opening.

The closure element 16 of the pipe encircling means 11 is in the nature of a closure or gate means for the outer end of the opening 19 and may be any suitable form of gate or closure. In the particular form of the invention illustrated the gate element 16 includes two sections pivotally carried by the body part 15. One section 22 of the gate element 16 is pivotally mounted on the outer end of the part 17 and the other section 23 of the gate is pivotally supported on the outer end of the side part 18. The sections 22 and 23 may be pivotally connected with the body part 15 by pivot pins or bolts 24. The two sections 22 and 23 are shaped to embrace or extend around a pipe P to retain the pipe in position for engagement by the gripping element 11. 100 The inner sides of the sections 22 and 23 may 105 110

be curved to effectively seat against the pipe P. In the particular case illustrated the inner sides of the sections 22 and 23 are provided with pipe holding parts in the form of dies 25. The dies 5 may be seated in sockets or recesses 26 and may have teeth for engaging the pipe.

The sections 22 and 23 are mounted on the body part 15 so that they are adapted to be swung or operated to a closed position where 10 their outer or free ends are in approximate abutment. Means is provided for releasably holding or latching the sections 22 and 23 together in the closed position. A latch 27 may be provided on one of the sections to cooperate 15 with a latch catch or lug 28 on the other section. In the case illustrated the latch 27 is pivotally carried by the section 23 and is adapted to cooperate with the lug 28 on the section 22. The latch 27 is pivotally attached to the section 20 23 by means of a pivot pin 29 and is positioned to engage or cooperate with the lug 28 upon the sections 22 and 23 being operated to the closed position. It is preferred to normally yieldingly urge the latch into a position where it will automatically cooperate with the lug 28 upon the 25 closure of the sections. A spring 30 may be provided in connection with the pivot pin 29 for yieldingly holding the latch 27 in a position to cooperate with the lug 28. Suitable operating 30 handles 31 may be provided on the outer sides of the closure sections 22 and 23.

The jaw 11 is carried by the main or body part 15 of the means 10 and is in the nature of a gripping element for securely gripping an 35 object such as the pipe P. The gripping jaw 11 is slidably carried in the opening 19 of the body 15 and is operable by means 13 to engage the pipe P. The jaw 11 may be a rigid unitary member. The jaw 11 is provided with flat 40 parallel sides 32 slidable on the inner walls 21 of the opening 19. The outer or active pipe engaging end of the jaw 11 is rounded or made concave to effectively seat against the pipe. The outer side of the jaw 11 may be provided with 45 pipe engaging parts in the form of dies 33.

In accordance with the preferred form of the 50 invention means is provided on the jaw 11 for engaging the pipe P to resist rotation of the element 11, and accordingly the tool, relative to the pipe P to ensure proper engagement of the element with the pipe when operation of the tool first starts. Any suitable form of yielding engagement means may be provided in connection 55 with the element 11 for engaging the pipe. In the case shown a pipe engaging member 40 is pivotally mounted in a recess 41 in the active or pipe receiving end of the jaw. The member 40 may be carried on a pin 43. The member 40 is so arranged so that its outer side normally 60 projects or extends beyond the outer side of the jaw 11 and the outer side is serrated or provided with gripping parts to engage the pipe P. A spring 42 is arranged in the recess 41 to normally 65 urge the gripping member 40 into engagement with the pipe P.

The handle 12 is provided on the main or body 70 part 15 of the means 10 to facilitate handling and operation of the tool. The handle 12 carries the means 13 for operating the gripping jaw 11. The handle 12 may be formed integral with the body part 15 and projects rearwardly or outwardly from the body part 15. The outer portion or end of the handle 12 is yoked or provided with spaced side parts 46 forming a transverse opening 45.

The means 13 for operating the gripping jaw 11 is adapted to be directly actuated by an operating line 46^a. The means 13 is carried by the handle 12 and is in the nature of cam means. The means 13 includes two main parts or elements, namely, a cam 50 and a push or operating rod 51 connected with the gripping jaw 11 and adapted to be operated by the cam 50. The cam 50 is pivotally mounted in the space 45 between the side parts 46 at the outer end of the handle 12 on a pin or bolt 52 extending transversely through the space or opening 45. The upper and lower ends of the cam 50 may be guided or supported by the inner sides of the side parts 46. The cam 50 includes an eccentric 80 or cam part 53 to cooperate with the rod 51 and a projecting lever or arm 54. The cam part 53 is positioned and proportioned to impart the desired inward movement to the rod 51 upon the cam 50 being rotated. The arm 54 is provided for operating the cam and projects radially outward from the central part of the cam. The arm 54 preferably projects to a point where the operating line 46^a connected to the arm will readily clear or pass the outer end of the handle 12. It is a feature of the invention that the cam 50 may be positioned so that the arm will be at the outer end of the handle so that the line 46^a can be operated to actuate the cam and also cause turning or operating of the tongs 85 as a whole. The arm being at the outer end of the handle, is located so that a substantial leverage is obtained for operating the tongs. The arm 54 is provided with suitable means for connection with the operating line 46^a. For instance, it may be provided with an opening 56 for receiving the operating line 46^a.

The operating rod 51 is slidably carried in a longitudinal opening 57 in the handle 12. The rod 51 extends completely through the opening 115 57 and one end of the arm is connected with the gripping jaw 11 while the other end of the rod projects into the opening 45 to be engaged by the cam 50. The inner end of the rod 51 may be screw threaded into a socket 58 at the 120 rear end of the gripping jaw 11. In accordance with the preferred form of the invention the outer end of the operating rod 51 is provided with an anti-friction roller 60 for engagement by the cam face 53. The outer end of the rod 125 51 may be yoked and the roller 60 may be rotatably carried between the yoked parts by a pin 61. Stop means is provided for limiting the inward movement of the operating rod 51. A stop 62 in the form of a collar is screw threaded 130 on the outer portion of the rod 51. The stop 62 is adapted to engage the inner end of the opening 45 to limit the inward movement of the rod 51 and the gripping jaw 11.

The means 14 for automatically returning the 135 gripping jaw 11 to the retracted position after actuation may be in the form of spring means. The means 40 may include a helical compression spring 65 arranged in a longitudinal slot or opening 66 in the handle 12. The spring 65 is 140 arranged between the outer end of the opening 66 and a pin 67 carried by the body part 15. The pin 67 extends transversely through the opening 66. The opening 66 is made sufficiently long to permit the desired movement of the rod 145 51. The spring 65 is arranged so that it is compressed upon inward movement of the gripping jaw 11 and, through expansion, operates to return the gripping jaw 11 to its normal position upon the release of the actuating means 13. As 150

the rod returns to the unactuated position the cam is likewise returned to the unactuated position.

In the preferred embodiment of our invention means is provided for returning the cam 50 to its unactuated position independently of the means above described. The opening 68 in the cam which passes the pivot bolt 52 may be provided with an enlargement 69 for carrying a spring 70. The spring 70 may be a helical spring surrounding the pivot bolt 52 and reacting between the cam 50 and the handle 12. The spring 70 has one end connected to the cam 50 and the other end secured to one of the side parts 46 of the handle 12. The spring 70 is such that it is subjected to a torsional strain upon rotation of the cam 50 and acts to rotate the cam 50 to return it to its normal position after actuation.

20 Means may be provided on the pipe engaging means 10 for suspending or carrying the tongs. In the form of the invention illustrated in the drawing an eye bolt 75 is provided on the body part 15, so that it projects upwardly from the 25 upper side of the part 15.

It is believed that the operation of the tool provided by this invention will be readily understood from the foregoing detailed description. A pull on the operating line 46^a which turns or 30 rotates the cam 50 causes the cam to operate the rod 51 and the gripping jaw 11. The cam face 53 and the lever arm 54 of the cam 50 may be proportioned and related to give the desired or necessary movement to the gripping 35 jaw 11. It is to be noted that the arm 54 may be proportioned to give the desired leverage to the cam 50. It is to be further noted that the cam

50 and the various other parts of the means 13 are carried at the outer portion of the handle 12 so that they may be made as heavy as desired or necessary without making the tool bulky or unbalanced. The various parts of the means 13 operate to balance the pipe engaging means 10 and other parts at the active end of the tool.

80 It is to be noted that the various parts of the tool may be proportioned so that the gripping element 11 has a substantial range of movement so that the tool is capable of handling objects varying considerably in size.

85 Having described only a typical preferred form of our invention, we do not wish to limit ourselves to the specific details set forth, but wish to reserve to ourselves any changes or variations that may appear to those skilled in the art or fall within the scope of the following claim.

90 Having described our invention, we claim:

95 Tongs of the character described including, pipe encircling means, a handle rigidly connected with said means, a jaw slidably carried by said means operable to grip a pipe, and means for actuating the jaw including a rod connected with the jaw and slidable in an opening in the 100 handle, a cam pivotally mounted on the outer end of the handle for operating the rod, means on the cam for receiving a line for turning the tongs, and means for limiting movement of the rod and jaw whereby the force transmitted by 105 the line may turn the tongs after actuation of the jaw, said last mentioned means including a collar adjustably screw-threaded on the rod adapted to engage a part of the handle.
